AIR CONDITIONER OR SIMILAR ARTICLE

David C. Eisendrath, Chicago, Ill., assignor to Cory Corporation, Chicago, Ill., a corporation of Delaware

Application July 10, 1957, Serial No. 46,898

Term of patent 7 years

(Cl. D62—4)

Figure 1 is a front elevational view of an air conditioner or similar article embodying the novel design;

Figure 2 is a fragmentary top plan view thereof;

Figure 3 is a left side elevational view thereof;

Figure 4 is a right side elevational view thereof with a portion broken away for convenience of illustration only.

The back of the air conditioner or similar article is plain.

I claim:

The ornamental design for an air conditioner or similar article, as shown and described.
